UNITED STATES PATENT OFFICE.

AUGUST E. SCHULTZ, OF CHICAGO, ILLINOIS.

BUMPING-POST.

No. 901,196.

Specification of Letters Patent.

Patented Oct. 13, 1908.

Application filed May 28, 1908. Serial No. 435,403.

To all whom it may concern:

Be it known that I, AUGUST E. SCHULTZ, citizen of the United States, residing at Chicago, in the county of Cook and State 5 of Illinois, have invented a certain new and useful Improvement in Bumping-Posts, of which the following is a full, clear, concise, and exact description, reference being had to the accompanying drawings, forming a part 10 of this specification.

My invention relates to bumping posts and will be well understood in connection with a specific description of one embodiment thereof found in the accompanying drawing, in which—

Figure 1 is a sectional elevation on line 1 1 of Fig. 2. Fig. 2 is a plan view of the structure illustrated in Fig. 1. Fig. 3 is a plan view of a part of the structure on line 20 3 3 of Fig. 1. Fig. 4 is a plan view of a part of the structure on line 4 4 of Fig. 1. Fig. 5 is a sectional view of a part of the structure on line 5 5 of Fig. 1. Fig. 6 is a view in cross-section of a part of the structure on 25 line 6 6 of Fig. 4.

Like parts are indicated by similar characters of reference throughout the different figures.

The bumping post of my invention is well 30 adapted to be supported upon the ordinary cross ties *a* and may be conveniently constructed mainly out of ordinary traction rails found in steam railroad practice, though I do not limit myself to the shape 35 of the rails. The bumping post includes, generally speaking, three main elements, one including the rear inclined rails *b b*, another including the forward inclined rails *c c* and the third including the horizontally 40 disposed rails *d d* which serve to tie together the bases of the rails *b* with the bases of the rails *c* as illustrated. While the rails *d* thus couple the rails *b b*, *c c*, these rails *d d* are in turn coupled with the main track 45 rails *e e* that are located in front of the bumping post structure, this union between the base rails *d d* and the traction rails *e e* being preferably effected by means of the construction illustrated most clearly in Fig. 50 4, where I have shown a filler block *f*, preferably of metal, interposed between the webs of the rails *d e*, these rail webs being clamped into engagement with said filler block *f* by means of clamping bolts *g*. By 55 means of the structure thus described a very rigid union is effected between the traction

rails *e* and the base rails *d*. As the bumping post is constructed, the elements *c* are in effect converging continuations of the traction rails *e*. The base portions of the elements *c* are secured with respect to the traction rails *e* and the base rails *d* by means of the elements *f* and *g* which have been described. I further insure the rigid interrelation of the sloping members *c* of the bumping post with the base rails *d* of the bumping post by means of the clamping braces *h* which engage the flanges and the tread surfaces of the rails *c d* to hold the same firmly together and prevent relative 70 vertical displacement thereof.

The bases of the sloping members *b b* are united with the base rails or elements *d* in much the same manner as the base portions of the elements *c* are with said rail portions 75 *d*, the manner of uniting the base portions of the elements *b b* with the base portions *d* being illustrated most clearly in Fig. 3, where I have illustrated a filler block *i* interposed between the webs of the rails *b b d d*, and clamping bolts *k* that secure the rail webs and the filler block rigidly in relation to each other. Inasmuch as there is no lifting tendency at the base portions of the rail sections *b b*, the rear of the bumping post 85 structure need not be clamped in relation to the ties, and therefore the rear portion of the bumping posts merely rests upon the ties. The inclined elements *c c* of the bumping post structure converge upwardly, as do the 90 elements *b b*, and the elements *b b* slope toward the elements *c c*, the rail sections *c c* being inter-connected with the rail sections *b b* by means of the structural devices now to be set forth.

As shown, the rails or inclined members *b b* pass at their upper ends between the oppositely inclined members *c c*, there being provided upon the inner faces of the inclined members *c c*, shelves *l* (Figs. 1 and 5) that 100 serve to prevent the improper depression of the rail sections *b b*. On the other hand, the rail sections or inclined members *b b* are prevented from undue elevation by means of a member *m* which passes through the upper 105 ends of the rail sections *c* and is received in grooves *n* formed in the upper faces of the elements *b b*. The normal relation of the elements *b b* with the elements *c c* is preferably such that the elements *b b* normally rest 110 upon the shelves *l*, the rod *m* then not entering fully into the grooves *n*. When, how-

ever, the bumping block *o* is forcibly impinged upon by the coupler of a bumping car, the elements *b b* are rocked very slightly, the rod *m* thereupon being bottomed in the 5 grooves *n*. These grooves *n* are continued in the base of the block *o* which is bolted between the rail sections *b* by means of bolts *o*.

In completing the device of my invention, I provide means whereby the force of the 10 blows received by the bumping block *o* is restrained from having shearing action upon the bolts *g* and *k* which establish the interconnection of the bumping post structure with the traction rails *e*. To this end, I provide key devices in the form of plates *p* passing through oblong slots in the webs of the rails *b b*, *d d* and the webs of the rails 15 *c c*, *d d*. In order that the bolts *g* may have their clamping action properly effected, and for other reasons well known to those skilled 20 in the art, fish plates *q* are interposed between the bolt heads and nuts and the webs of the rails.

The base portions of the rail sections *b b* 25 are continued horizontally, to which end the rail sections *b b*, *c c* are bent when the regions of their bases are reached.

The advantages of the bumping post of my invention will be readily understood by 30 those skilled in the art.

Having thus described my invention, I claim as new and desire to secure by Letters Patent the following:—

1. A railway bumping post including base 35 rails *d d*, the upwardly and rearwardly inclined rail sections *c c*, the upwardly and forwardly inclined rail sections *b b*, the rail sections *c c* converging upwardly and the rail sections *b b* converging upwardly, traction rails *e e* continued from the rail sections *c c*, filler blocks *f* interposed between the webs of the rail sections *d d* and the alined webs of the rail elements *c c*, *e e*, bolts *g* passing through said filler blocks, filler 45 blocks *i* interposed between the base portions of the rail sections *b b* and the rail sections *d d*, bolts *k* passing through said filler blocks and webs, key plates *p p* passing through the webs of the rail portions united by the bolts 50 *g* and *k*, shelves *l* for engaging the upper ends of the rail sections *b* and carried by the rail sections *c*, a rod *m* carried by the rail section *c* and extending over the rail sections *b* to limit the upward movement of the rail 55 sections *b*, and a bumping block *o* provided upon the upper ends of the rail sections *b*.

2. A railway bumping post including base 60 rails *d d*, the upwardly converging and rearwardly inclined rail sections *c c*, the upwardly converging and forwardly inclined rail sections *b b*, the base rail sections *d d* being united with the bases of the rail sections *b b*, *c c*, a bumping block *o* carried by the rail sections *b b*, and a key plate passing through 65 openings in the rail sections *d b*.

3. A railway bumping post including base rails *d d*, the upwardly converging and rearwardly inclined rail sections *c c*, the upwardly converging and forwardly inclined rail sections *b b*, the base rail sections *d d* 70 being united with the bases of the rail sections *b c*, a bumping block *o* carried by the rail sections *b b*, means for restricting the relative motion between the rail sections *b* and the rail sections *c*, and a key plate passing through openings in the rail sections *d b*.

4. A railway bumping post including base rails *d d*, the upwardly converging and rearwardly inclined rail sections *c c*, the upwardly converging and forwardly inclined 80 rail sections *b b*, the base rail sections *d d* being united with the bases of the rail sections *b c*, the rail sections *b* crossing the rail sections *c* at their upper ends, a bumping block *o* carried by the rail sections *b b*, and 85 a key plate passing through openings in the rail sections *d b*.

5. A railway bumping post including base rails *d d*, the upwardly converging and rearwardly inclined rail sections *c c*, the upwardly converging and forwardly inclined 90 rail sections *b b*, the base rail sections *d d* being united with the bases of the rail sections *b c*, the rail sections *b* crossing the rail sections *c* at their upper ends, a bumping block *o* carried by the rail sections *b b*, means for restricting the relative motion between the rail sections *b* and the rail sections *c*, and a key plate passing through openings 95 in the rail sections *d b*.

6. A railway bumping post including base rails *d d*, the upwardly converging and rearwardly inclined rail sections *c c*, the upwardly converging and forwardly inclined rail sections *b b*, the base rail sections *d d* 100 being united with the bases of the rail sections *b c*, the rail sections *b* crossing the rail sections *c* at their upper ends, a bumping block *o* carried by the rail sections *b b*, means inter-relating with the rail sections *b b*, *c c* to prevent undue elevation and depression of the rail sections *b b*, and a key plate passing through openings in the rail sections *d b*.

7. A railway bumping post including base rails *d d*, the upwardly converging and rearwardly inclined rail sections *c c*, the upwardly converging and forwardly inclined rail sections *b b*, the base rail sections *d d* 115 being united with the bases of the rail sections *b c*, a bumping block *o* carried by the rail sections *b b*, fastening bolts for uniting the rail sections *d d* with the bases of the rail sections *b b*, *c c*, and key plates *p* passing through openings in the rails *d d*, *b b* and *c c* to relieve said bolts of shearing strain.

8. A railway bumping post including base rails *d d*, the upwardly converging and rearwardly inclined rail sections *c c*, the upwardly converging and forwardly inclined 120 rail sections *b b*.

5 rail sections b b , the base rail sections d d being united with the bases of the rail sections b c , a bumping block o carried by the rail sections b b , means for restricting the relative motion between the rail sections b and the rail sections c , fastening bolts for uniting the rail sections d d with the bases of the rail sections b b , c c , and key plates p passing through openings in the rails d d , b b and c c to relieve said bolts of shearing strain.

9. A railway bumping post including base rails d d , the upwardly converging and rearwardly inclined rail sections c c , the upwardly converging and forwardly inclined rail sections b b , the base rail sections d d being united with the bases of the rail sections b c , the rail sections b crossing the rail sections c at their upper ends, a bumping block o carried by the rail sections b b , fastening bolts for uniting the rail sections d d with the bases of the rail sections b b , c c , and key plates p passing through openings in the rails d d , b b and c c to relieve said bolts of shearing strain.

10. A railway bumping post including base rails d d , the upwardly converging and rearwardly inclined rail sections c c , the upwardly converging and forwardly inclined rail sections b b , the base rail sections d d being united with the bases of the rail sections b c , the rail sections b crossing the rail sections c at their upper ends, a bumping block o carried by the rail sections b b , means for restricting the relative motion between the rail sections b and the rail sections c , fas-

tening bolts for uniting the rail sections d d with the bases of the rail sections b b , c c , and key plates p passing through openings in the rails d d , b b and c c to relieve said bolts of shearing strain. 40

11. A railway bumping post including base rails d d , the upwardly converging and rearwardly inclined rail sections c c , the upwardly converging and forwardly inclined rail sections b b , the base rail sections d d being united with the bases of the rail sections b c , the rail sections b crossing the rail sections c at their upper ends, a bumping block o carried by the rail sections b b , 50 means inter-relating with the rail sections b b , c c to prevent undue elevation and depression of the rail sections b b , fastening bolts for uniting the rail sections d d with the bases of the rail sections b b , c c , and key plates p passing through openings in the rails d d , b b and c c to relieve said bolts of shearing strain. 55

12. A railway bumping post including base rails d d , a bumping block, rail sections b intervening between the bumping block and base rails and united at their lower ends with the base rails, and a key plate passing through openings provided in the rail portions d b near where they are united. 60

In witness whereof, I hereunto subscribe my name this 25th day of May A. D., 1908.

AUGUST E. SCHULTZ.
